UNITED STATES PATENT OFFICE.

JAMES J. HENNESSY, OF ST. LOUIS, MISSOURI.

AUTOMATIC LUBRICATOR.

1,142,705.

Specification of Letters Patent. Patented June 8, 1915.

Application filed February 2, 1914. Serial No. 815,870.

To all whom it may concern:

Be it known that I, JAMES J. HENNESSY, a citizen of the United States, and resident of St. Louis, Missouri, have invented certain new and useful Improvements in Automatic Lubricators, of which the following is a specification.

This invention relates to improvements in lubricators, more especially applicable for use on locomotives and has for its object a mechanism which is manipulated automatically by the starting and stopping of the engine.

A further object of my invention is to construct a lubricator provided with a double head piston, against which live steam is directed for manipulating a valve for automatically regulating the flow of the oil from the oil receptacle to the engine cylinder or other parts to be lubricated.

A further object of my invention, is to construct a lubricator which will open and permit the oil to circulate automatically with the starting of the engine, and to close automatically when the engine is stopped.

Figure 1 is a vertical sectional view of my improved lubricator. Fig. 2 is an enlarged detail sectional view of the valve mechanism made use of through which the condensation is admitted into and discharged near the bottom of the oil receptacle. Fig. 3 is a bottom plan view of the valve. Fig. 4 is an enlarged detail sectional view of the check valve made use of in the steam inlet pipe.

In carrying out my invention I provide a lubricator consisting of a tubular member 5, its upper end flaring outwardly forming a piston cylinder 6, the bottom end of the tubular member 5 being suitably threaded and seated in a liquid condenser 7; this condenser is provided with a partition wall 8 having a central downwardly projecting tube 9, which extends into an oil receptacle 10. In the piston cylinder 6 is located a piston head 11 to which is attached a valve stem 12, which extends downwardly through the tubular member 5, and into a liquid condenser 7. The bottom end of said stem is provided with a valve 13 which is located in a valve casing 14 located on the top of the tube 9. On said valve stem is also located a piston head 15, which is of smaller diameter than the piston head 11, and which conforms with the radius of the interior of the tubular member 5; this piston head is

separated a reasonable distance from the piston head 11, and the downward movement of the piston head is limited by a flange or internal rib 16 located on the interior of the tubular member 5.

The flaring portion of the tubular member is preferably mounted as shown, and is provided with a shoulder 17, which acts as a supporting seat for a spring 18, which encircles the valve stem 12, and contacts with the under surface of the piston head 11; the two piston heads are properly spaced apart by means of a sleeve 19 located between both heads and encircling the valve stem 12.

On the top of the piston cylinder 6 is located a liquid receptacle 20, the same being detachably connected as shown, and that portion of the bottom 21 of the receptacle which acts as the cover for the cylinder 6 is provided with a small opening 22 through which the liquid from the receptacle 20 is permitted to pass into the cylinder 6, and rest upon the top of the piston 11, the purpose of which will be fully hereinafter described. To the top of the liquid receptacle 20 is connected a pipe 23, which is a branch of the pipe 24 leading to the steam chest; this pipe continuing downwardly also leading into the piston cylinder 6 at a point above the top of the piston head 11, and is provided with a check valve 25, the construction of which is clearly shown in Fig. 4; this check valve is provided with a spring-actuated valve head 26 normally seated in the valve seat 27, and as the steam pressure is admitted into the steam chest of the cylinder it also enters the pipe 24 connected thereto, the valve is opened and steam admitted into the cylinder 6 above the piston head 11.

In the tubular member 5 is located a pipe connection 28, which leads to the steam dome of the locomotive and through which live steam is admitted into the tubular member 5, and condenser 7; all condensation of the steam lodging in the condenser 7, and which condensation is permitted to flow downwardly through the tube 9 into the oil receptacle 10 whenever the valve 13 is depressed; the normal tendency of the steam pressure admitted through the pipe 28 connected to the steam dome of the boiler is to hold the valve 13 closed by means of the steam pressure against the bottom of the piston head 15.

The oil receptacle 10 is detachably connected to the liquid condenser 7 as shown, the said condenser being provided with a horizontal partition wall 29, spaced a reasonable distance above the bottom 30 forming an oil chamber 31; from this oil chamber leads an inlet pipe 32 projecting upwardly, its top being a short distance from the bottom of the horizontal wall 8, and through which the oil located in the receptacle 10 is fed from the receptacle into the chamber 31 as the condensation or water fed from the condenser 7 enters into and near the bottom of the receptacle 10, which tendency is to force the oil upwardly. The oil which feeds into the chamber 31 is then permitted to pass through the jets 32' into the sight feeds 33, and then pass outwardly through the openings 34 into the proper pipe connections and is fed drop by drop from this point to the engine steam chest and cylinder or any other location to which the pipe is connected.

The feed is regulated by means of the needle valves 35, and the same are regulated to the required amount of oil to be fed before the locomotive leaves the round-house, and in order to prevent tampering with the regulation, a hood or cover 36 is placed over the same and secured by an ordinary lock 37.

The operation of my invention is as follows: The receptacle 10 is filled with oil, either by a separate inlet, or by detaching the same from the condenser 7. Liquid is admitted into the receptacle 20 and the valve 13 is held normally closed by means of the spring 18. Steam is admitted into the tubular member 5 through the pipe 28 which is connected to the steam dome of the boiler, the pressure of said steam assisting in normally holding the valve closed, and the condenser 7 is supplied with water by the condensation of the steam. When the locomotive is operated and steam admitted into the steam chest for operating the engine; steam is likewise admitted through the pipe connection 24 attached to the steam chest into the liquid receptacle 20, and above the piston 11, the radius of the piston 11 being greater than the piston 15, the steam pressure admitted above the piston 11 has a tendency to press the same downwardly opening the valve 13 allowing the water of condensation to pass from the condenser 7 down into and near the bottom of the oil receptacle 10, and by the feeding of the water below the oil line will force the oil upwardly and permit it to flow downwardly through the tube 32 into the chamber 31, and then out through the sight feeds 33 into the tube connection, which leads to the cylinder or steam chest. Whenever the steam is cut off from the steam chest of the engine, the pressure of the steam in the tubular member 5, below the piston head 15 has a tendency to

close the valve to check the flow of water, and also the feed of the oil; this closing feature is then gradually and slowly closed by means of the liquid located in the piston cylinder above the piston head 11, as the upward pressure of the piston head 11 forces the liquid back into the receptacle 20 through the aperture or opening 22. This gradual flow of the liquid from the piston cylinder back to the liquid receptacle acts as a cushion, permitting the valve to close gradually and slowly while the locomotive is drifting and the steam from the steam chest cut off so that oil is continuously and slowly fed into the cylinder during that period. This is one of the essential features and objects of my invention: to supply oil to the cylinder while the engine is in operation, and also while the locomotive is drifting, but to automatically stop the flow of oil when the locomotive is at a stand still.

Having fully described my invention what I claim is:

1. In a condensation displacement lubricator, comprising a lubricant receptacle, a condenser mounted above same, a piston chamber mounted above the condenser, a plurality of pistons mounted on a piston rod operated in said piston chamber a piston rod extending into the condenser and forming a valve stem; a passage way connecting the lubricant receptacle and condenser, a valve located in said passage way and mounted on the valve stem for controlling the flow of the water from the condenser, a steam connection to the condenser and piston chamber, and an outlet from the lubricator, substantially as specified.

2. In a condensation displacement lubricator, the combination of a lubricant receptacle, a condenser, a steam connection to the condenser a valve controlled passage way connecting the lubricant receptacle and condenser; a double piston chamber mounted above the condenser, pistons mounted within the piston chamber, a piston rod connecting the pistons and extending into the condenser; a valve located on the lower end of said piston rod and seated in the passage connecting the lubricant receptacle and condenser; means for supplying steam to the piston chamber when the source of steam is open, said steam operating one of said pistons, and opening the valve between the lubricant receptacle and condenser, and a means for admitting steam to the other piston when the first named source of supply is cut-off for effecting the shut-off of the condenser valve, substantially as specified.

3. In a condensation displacement lubricator, the combination of a lubricant receptacle, a condenser, an outlet tube leading from the bottom of the condenser to a point near the bottom of the lubricant receptacle,

lubricant outlet means connected with the receptacle, a tubular member having a flaring upper end connected to the condenser and provided with large and small piston chambers, a receptacle connected to the flared end of the tubular member and closing the upper piston chamber, the receptacle being provided with a port communicating with upper piston chamber, a piston in the upper piston chamber, a spring beneath said piston, a piston in the lower piston chamber, a valve in the upper portion of the condenser outlet tube, a rod connected to the valve and secured to the two pistons, a steam pipe communicating with the tubular mem-

ber beneath the lower piston and adapted to be connected with a source of steam pressure, a steam pipe communicating with the upper piston chamber above the piston therein and with the chamber thereabove, the latter steam pipe being adapted to be connected with a source of controllable steam pressure.

In testimony whereof I have signed my name to this specification, in presence of 25 two subscribing witnesses.

JAMES J. HENNESSY.
